TOILET SEAT

Harper Richards, Chicago, Ill.

Application October 6, 1947, Serial No. 778,669

6 Claims. (Cl. 4-239)

1

This invention relates to a toilet seat adapted to be folded into small compass for convenience in portability. The seat may readily be placed in a small case or envelop when not in use. It will be found particularly advantageous for infants and small children.

The features of improvement herein to be described pertain to the joining of four arcuate seat sections in such a manner that they may fold together to occupy a minimum of space. These joints which comprise opposed hinges and opposed pivots, are amply strong to sustain the sections in operative position. The entire structure may be produced at relatively small expense, it is light and convenient to handle, and it may be relied upon to give prolonged and dependable service.

A suggestive embodiment of my invention is set forth in the accompanying drawing wherein:

Figure 1 is a perspective view of the toilet seat opened out ready for use;

Fig. 2 which is a similar view shows the seat in a first stage of the folding operation;

Fig. 3 is a similar view showing the seat in its finally folded state;

Fig. 4 is a top plan view showing the seat opened out in operative position;

Fig. 5 is a sectional detail view, taken on line 5-5 of Fig. 4;

Fig. 6 is a view in plan of the seat in its fully folded state;

Fig. 7 is a fragmentary detail in section, taken on line 7-7 of Fig. 2; and

Fig. 8 is an elevational edge view of the folded seat, looking from the line 8-8 of Fig. 6.

The seat comprises four sections interconnected by opposed hinges and pivots to form a generally rectangular frame having a central elongated opening. The two rear sections A and B which are alike in all respects are connected by a hinge having leaves a and b, each joined to one of the sections. The hinge pintle 10 is substantially aligned with the longitudinal axis of the seat opening.

The section A has an inner edge 12 which is arcuate to join with a similarly formed edge 14 of the companion rear section B. The arcuate edges of the two sections together extend through slightly more than 180° to define a major part of the seat opening which is slightly elongated in form.

Each of the seat sections may be formed of any suitable material such as wood, plywood, plastic, etc. Two forward sections C and D are also provided to complete the seat. These sections are alike, being connected by a hinge having leaves c and d each affixed to one of the sections. The pintle 15 for this latter hinge is also aligned with the longitudinal axis of the seat opening. The inner edges 16 and 18 of the sections C and D

2

respectively are of generally arcuate form to join with each other and with the arcuate edges 12 and 14 so as to provide a central opening having a smooth continuous edge.

Each of the two forward sections C and D is connected to the associated rear section A or B by pivot means which are identical. For this purpose there is affixed to the forward section C at its rearward end a plate 20 having a generally triangular tongue 21 which extends beyond that section to overlap the end of the adjacent section A and, in turn, to be overlapped by a complementary plate 22 which is affixed to the section A from which it is spaced by thickened marginal walls 23 the requisite distance to provide a narrow pocket for accommodation of the tongue 21. In like manner the section D carries a similar plate 30 formed with a projecting tongue 31 which fits within a narrow pocket provided by an overlapping plate 32 affixed to the section B from which it is spaced by thickened marginal walls 33. At a point between the abutting ends of the sections A and C close to the inner edges thereof a pin 25 extends through the complementary plates 20 and 22 to establish a pivotal connection therebetween. A similar pivotal connection between the complementary plates 30 and 32 is provided by a second pin 35 whose location is relatively the same as the pin 25.

It will be noted that the longitudinal axis of the seat is substantially co-axial with that of the two pintles 10 and 15. The seat may accordingly be broken along this hinge line so as to fold over in the form of two plies, as suggested in Fig. 2. The axes of the pivot pins 25 and 35 are parallel, transversely of the plane of the seat, and equidistantly located opposite its longitudinal axis on directly opposite sides thereof. In consequence, when the seat is given its first fold so as to reach the position of Fig. 2, the two pins 25 and 35 will be brought to coaxial positions substantially in end to end relation. When so disposed, but not until then, the sections C and D may be folded in unison about the coaxial pins 25 and 35 which pivotally connect them to the sections A and B. When this is done the seat will be reduced to the compact form and size which is shown in Figs. 3 and 6. Here it will be observed the two front sections C and D, one lying against the other, are brought into proximity with the two back sections A and B which also lie against each other, the curved opening therebetween being substantially occupied by the folded sections C and D when in this folded state.

The seat may then be fitted into a small case or envelope, which will protect it while stowed away in a bag or other receptacle. When its use is again desired, a reverse procedure for opening the seat up is followed. This involves first a swinging movement about the two pivot pins 25 and

35 to extend the front sections outwardly of the rear sections, and then a further movement about the coaxial hinges to bring all four sections into a single plane.

The hinge connections are desirably affixed to the under side of the seat. They may be recessed or countersunk therein, or the under side of the seat may be faced with material which will cause the hinges to occupy relatively sunken positions. These and other details of construction may be optionally added to the seat but without in any wise affecting its novel character.

In summary, the seat comprises four arcuate sections arranged end to end in abutting relation to define a fully closed opening having a longitudinal axis, the two sections at one end of the seat being counterparts and the two sections at the other end of the seat also being counterparts but unlike the two sections first noted; and connecting means between the sections whereby they may be folded once about the longitudinal axis and thereafter folded again about a common axis in a plane transversely of the longitudinal axis about two pivotal connections which, in the fully extended condition of the seat, are disposed with their axes transversely of the plane thereof on opposite sides of the longitudinal axis and equidistant therefrom. By such a construction the seat is first doubled upon itself, then closed inwardly to occupy a minimum space for stowage or for carrying.

I claim:

1. A folding toilet seat having a longitudinal axis comprising a pair of like arcuate sections on opposite sides of the longitudinal axis at one end of the seat and a second pair of like arcuate sections, on opposite sides of the longitudinal axis at the opposite end of the seat, each of the sections being arranged in end to end abutting relation with the adjacent sections, pivotal connections on opposite sides of the longitudinal axis of the seat having their axes disposed transversely of the plane of the seat and joining one section of each pair with the adjacent section of the other pair, and hinge connections having their axes in mutual alignment with each other and with the longitudinal axis of the seat interconnecting two adjacent arcuate sections on opposite sides of the longitudinal axis of the seat.

2. A folding toilet seat having a longitudinal axis comprising a pair of like arcuate sections on opposite sides of the longitudinal axis at one end of the seat and a second pair of like arcuate sections, unlike the first pair of arcuate sections, disposed on opposite sides of the longitudinal axis at the opposite end of the seat, each of the sections being arranged in end to end abutting relation with the adjacent sections, pivotal connections on opposite sides of the longitudinal axis of the seat having their axes disposed transversely of the plane of the seat and joining one section of each pair with the adjacent section of the other pair, and hinge connections having their axes in mutual alignment with each other and with the longitudinal axis of the seat interconnecting two adjacent arcuate sections on opposite sides of the longitudinal axis of the seat.

3. A folding toilet seat comprising four arcuate sections arranged end to end to define a fully closed opening having a longitudinal axis on opposite sides of which the sections are symmetrically disposed, a hinge connection having its axis aligned with the longitudinal axis of the

5 seat joining each of the two arcuate sections at opposite ends of the seat, and two pivotal connections each having its axis transversely of the plane of the seat, disposed at points equidistant from the longitudinal axis of the seat and oppositely of each other joining each of the two arcuate sections at opposite sides of the seat.

4. A folding toilet seat comprising four arcuate sections arranged end to end in abutting relation to define a fully closed opening having a longitudinal axis on opposite sides of which the sections are symmetrically disposed, a hinge connection having its axis aligned with the longitudinal axis of the seat joining each of the two arcuate sections at opposite ends of the seat in a manner to permit a folding thereof through substantially 180°, and two pivotal connections joining each of the two remaining arcuate sections at opposite sides of the seat, the pivotal connections having their axes disposed at points equidistant from the longitudinal axis of the seat, transversely of the plane of the seat, oppositely of each other, adapted to occupy coaxial positions when the seat is once folded about its 15 longitudinal axis to permit a further folding thereof about the common axis of the pivotal connections whereby the two sections at one end of the seat may be swung toward the two opposite sections to a position within the arcuate contour thereof.

5. A folding toilet seat comprising four arcuate sections arranged end to end in abutting relation to define a fully closed opening having a longitudinal axis, the two sections oppositely of the 20 longitudinal axis at one end of the seat being alike and the two sections oppositely of the longitudinal axis at the other end of the seat being alike but unlike the two sections first named, hinge connections between each of the two like sections at opposite ends of the seat in line with the longitudinal axis thereof, and pivotal connections between each of the two unlike sections at opposite sides of the seat disposed equidistantly from its longitudinal axis and oppositely of each 25 other with their axes transversely of the plane of the seat adapted to occupy coaxial positions when the seat is once folded about the common axis of the two hinge connections to then permit one pair of like sections to swing toward the other pair of like sections into nesting relation therewith.

6. A folding toilet seat comprising two pairs of arcuate sections arranged end to end to define a fully closed opening, the two sections of each 30 pair being disposed on opposite sides of a line extending diametrically of the seat, a hinge connection having its axis aligned with the line extending diametrically of the seat joining the two arcuate sections of each pair, and two pivotal 35 connections each having its axis transversely of the plane of the seat, disposed at points equidistant from the line extending diametrically of the seat and oppositely of each other, joining two arcuate sections of opposite pairs.
